UNITED STATES PATENT OFFICE.

MERTON S. MUNN, OF STILLWATER, MINNESOTA.

TRUCK AND AXLE MECHANISM FOR RAILWAY-CARS.

1,105,291.

Specification of Letters Patent. Patented July 28, 1914.

Application filed November 28, 1913. Serial No. 803,476.

To all whom it may concern:

Be it known that I, MERTON S. MUNN, a citizen of the United States, residing at Stillwater, in the county of Washington and State of Minnesota, have invented a new and useful Truck and Axle Mechanism for Railway-Cars, of which the following is a specification.

My invention relates to truck and axle mechanism for railway cars; and the principal object is to prevent wear and tear of the flanges of the car wheels and the adjacent sides of the rails against each other in running over curves of a track, and at the same time to prevent possible spreading of the rails from lateral pressure by the flanges of the wheels against the outer or longer rail of the curve.

This and other objects I attain by providing each car with a mechanism which is operated by compressed air and arranged to turn each truck of the car in the direction of the curve of the track; said mechanism being thrown into action and out of action by having certain levers arranged to contact with blocks fixed on the road bed near each end of each curve of the track.

In the accompanying drawings, Figure 1 is a side elevation of a simple railway car standing on a track and embodying my invention. Fig. 2 is a top or plan view of what is shown in Fig. 1, except that the rail ties are omitted and the car body is shown only in dotted outline, and the operating cylinder is shown in diametrical section. Fig. 3 is an enlarged sectional view about as on the line *a—a*, Fig. 2, and with the middle portion of the beam 39 in Fig. 1 broken away, showing one of the air-controlling valves in what may conveniently be termed idle position. Fig. 4 is the same as Fig. 3, only that the valve plug stands in what may be termed active position, because when the valve is in that position the mechanism will act on the trucks to turn them. Fig. 5 is an enlarged diametrical section of one of the car wheels and its axle and journal, disclosing means for lubricating the axle in the wheel. Fig. 6 is a plan view of a railway track having two opposite curves and actuating blocks adjacent thereto, and on the track is shown a flat car arranged to move in either direction of the track. This view being on a comparatively small scale only a few parts of the mechanism are either indicated in dotted lines or shown through

notches formed in the car floor by breaking away portions near the four corners of same, since the mechanism is fully shown in the other views, so Fig. 6 is only to aid in the explanation of the operation when the car is run in different directions and over right and left curves.

Referring to the drawings by reference numerals, 1 designates the ties and 2 the rails of a railway track which may have several curves to the one side or the other; of such curves two are shown in Fig. 6 and are there marked at their outer sides A and B.

Fixed on the ties, or otherwise on the road bed, are two blocks, C and D, best shown in Fig. 1 to be highest in the middle and inclined toward both ends; the blocks D are near the outer side of the outer rail at one end of the curve, and the block C is nearer to the rail at the other end of the curve. The use of said blocks will presently be fully described.

The car body 3 is provided with the usual studs (not shown) projecting downward into the central holes 4* in the bolsters 4 of two trucks 5*, having wheels 5 with axles 6, the latter journaled in bearings 7, in which they may turn more or less or not at all, since each wheel, or at least one wheel on each axle rotates partly on and partly with a bushing 8 on the axle (see Fig. 5). Such rotation being necessary in order that none of the wheels may need to slide on the rail when the truck runs on a curve of the road. I also provide novel means for lubricating the wheel and the bushing thus arranged. Said means involve a central oil duct or chamber 9 in the shaft, with a branch duct 10 leading to the bushing 8, and holes 11 in the bushing to admit oil to the wheel and the outer side of the bushing. The oil duct 9 constitutes an oil cup, which is filled through a duct 12 in a plug 13, which is threaded into an enlarged end-portion of the duct 9 and is provided with a socket 14 for the insertion of a polygonal portion 15 of a T-wrench, or key 16, by which the plug is screwed home flush with the end of the axle, whereby the duct or oil-hole 12 is closed after the oil is poured in. The oil chamber 9 may extend all the way through the axle so that the oiling of both wheels may be done from one end of the axle; but both ends of the axle may also be arranged as shown in Fig. 5; or, the other end of the axle may be

constructed and oiled in the ordinary manner, since the axle is free to rotate in its regular bearings 7 and also in one of the wheels, and that will enable either wheel to 5 rotate faster than the other when the curve of the road so requires it. The bushing 8 is to provide two wearing surfaces and thereby lessen the danger of either surface running hot, and if one surface should heat and stick, 10 the other may work until the first one may cool off again.

The flange or collar 17 about the extreme end of the axle is to prevent longitudinal movement of the axle in one direction, and the shoulder 18 is to prevent such movement 15 in the other direction in the wheel and the bearing 7.

As best shown in Fig. 5, the flange 5^a of each wheel stands at right angles, as at 5^b, 20 to the face of the wheel, so that the latter will at all times bear upon the middle of the rail 2, while in ordinary railway construction the face of the wheel and the adjacent face of the wheel flange 5^a join at an obtuse 25 angle, by which both the wheel and the flange have a tendency to wear unduly out the inner side and top portion of the rail and also to spread the rails, especially the outer rail of a curve in passing over it. The 30 force against the outer rail is also due to the momentum of the car and the fact that the outer rail is depended on to force the trucks to make a curve while the wheels near the outer side of the curve resist such turning 35 by being dragged on the rail as much as the outer rail is longer than the inner one. It is these weak points about the old structures I am trying to remedy by my invention.

Secured underneath the car body is a reservoir 19 adapted to contain compressed air 40 furnished from the regular pipe 20 which supplies compressed air to the air-brakes of the train; said pipe 20 is connected to the reservoir by a hose 21 and a nipple 22, the 45 latter having a check-valve 23 (shown in Fig. 2) to prevent air from returning from the reservoir. The mechanism being the same at both sides of the car I will describe only one side, which is as follows: The reservoir 19 is connected with both ends of an 50 operating cylinder 25 by piping 24, in which are inserted two valves 26, which may be secured to the car body by brackets as indicated at 27 in Fig. 1; and the cylinder 25 is 55 secured by a bracket or hanger 28. In the cylinder is a piston 29 fixed on a piston-rod 30, whose projecting ends are each provided with pins 31 engaging in slots 32 in overlapping ends or arms of two bell-crank 60 levers 33; which are fulcrumed on posts 34 depending from the car; each lever 33 having its other arm pivoted at 35 to the adjacent end of a truck-turning rod 36, which has its opposite end pivoted at 37 to the bolster 65 4 of the truck.

The plug 38 of each valve 26 (see Figs. 3 and 4) is provided with a beam lever 39 forming two radial arms, each of which has a pin 40 engaging in a slotted hole 41 in one end of a rod 42; each of said rods having its other end provided with an eye 43 fitting loosely about the upper end of a normally vertically disposed actuating lever 44, or 44^a. Each actuating lever has its lower end provided with an antifriction wheel 45, 70 or 45^a, of which the wheel 45 is arranged to contact with the block C and the wheel 45^a to contact with the block D. Each lever 44 and 44^a has near its middle a slotted hole 46 (best shown to the right in Fig. 1), engaged by a pin 47 fixed in a pocket 48, which is secured at 49, one pocket to each end of the truck-bolsters 4, and has its upper edge provided with a V-shaped notch 50, in which a pin 51 of the actuating lever normally rests when the lever is in its lowest position on the fulcrum pin 47.

In Figs. 1 and 2 the blocks C and D must be imagined to be in the same relation to a curve as shown in Fig. 6, and they will aid 90 in explaining the operation of the device although the space does not permit to show them properly apart in said Figs 1 and 2.

The operation is as follows: The valve plugs 38, arms 39 and rods 42 normally occupy the positions shown in Fig. 3, so that the compressed air from the reservoir presses equally at both sides of the piston, thus leaving the trucks without any tendency to turn as long as the car is on a straight track. The reservoir being supplied with compressed air, either in the way already stated, by having connection with the piping for the air-brakes and the air-compressor belonging thereto, or a special 105 air-compressing device (not shown) may be carried by each car and operated by a friction wheel contacting with one of the car-wheels. Supposing thus that the reservoir and the cylinder are charged with compressed air, and it be desired to run the car over the curve B, in the direction of the arrow E; the wheel 45 will then contact with the block C and lift the lever of same with its pin 51 above the notch 50 of the pocket 110 and will thereupon tilt the lever sufficiently to cause the lower rod 42 to pull and thereby turn the valve plug to the position shown in Fig. 4, so that the air from the reservoir is cut off and the air in that end of the cylinder, nearest to the letter B in Fig. 6, will exhaust through the port 52 of the valve shell, and the air in the other end of the cylinder will move the piston 29 toward B, whereby the piston and the bell-crank levers 115 120 nearest B will push the rods 36 apart, and the bell-crank levers at the other side of the car will pull on the rods 36 and thereby give the trucks the required tendency to turn on their pivots as fast as the curve of the track 125 130

requires. As soon as the lever 44 has passed the block C it drops down to normal position in its pocket and thereby restores the rod 42 to normal position, as indicated in dotted line in Fig. 4; but the valve plug remains in the active position it was turned, and with its upper pin 40 moved to the inner terminal of the slot 41 of the upper rod 42. Now when the car has passed the curve B the wheel 45^a contacts with the block D, and acts by pushing on the upper rod 42 so as to rotate the valve plug back to the idle position shown in Fig. 3, so that the air pressure becomes again equal in both ends of the cylinder, and the trucks have no tendency to turn to either side. Now, if the same car returns over the curve B in the direction of the arrow F, the operation is the same as already described, except that the block D will act first and cause the lever with wheel 45^a to pull on the upper rod 42 and thus turn the valve plug to the active position in Fig. 4, and after the curve is passed the block C will act on the inner lever 45 and cause the lower rod 42 to push and thereby return the valve plug to its normal and idle position shown in Fig. 3. If the car is to run in either direction over the curve A, the valve 26 and all mechanism connected therewith at the other side of the car, the side nearest A, will serve so exactly in the same manner already described for the side B that there is no use in repeating the description; this is also obvious from the fact that if the sheet containing Fig. 6 be turned bottom edge upward and the letter A changed to B, the description of operation given is readable without alteration upon the curve really marked B. Such exact similarity of arrangement upon both sides of the car enables the device to work equally as well if the car should be reversed end-for-end on the track, as is sometimes done by passing cars over triangles or over a "Y" on the road, or by reversing it on a turn-table.

What I claim is:

1. For operation upon a railway track having a curve and a block fixed near each end of the curve, a car arranged to move on said track and having trucks with axles and wheels; said trucks pivoted underneath the car to turn in passing over curves, a double-acting cylinder fixed underneath the car and having a piston and a piston rod extending therefrom beyond the cylinder, rods operatively connecting the piston rod with the trucks to turn them, a reservoir and means for supplying the reservoir with compressed air, two valves arranged to normally admit compressed air from the reservoir into the two ends of the cylinder, each valve being constructed to shut off the air supply to the cylinder and exhaust air therefrom when turned in a certain position; actuating levers fulcrumed on the trucks arranged to contact

with the blocks near the track, and operative connections between said actuating levers and the valves, whereby each valve is alternately turned to active position when the car enters a curve and to idle position when the car leaves the curve. 70

2. For operation upon a railway track having curves to either side from the main track, and blocks fixed outside of each curve, one block near each end thereof, one block being nearer to the track than the other and having each two inclines sloping from the middle of the block toward each end thereof; a car arranged to move in either direction on the track and having swiveled trucks with flanged wheels to roll on the track; a double-acting cylinder fixed transversely underneath the car and having a piston with piston rods extending from both sides of it and out beyond the cylinder, two pairs of bell-crank levers fulcrumed underneath the car and operatively connected one pair with each piston rod, four longitudinal rods arranged two near each side of the car and having each one end pivotally connected with one of the trucks and the other end pivotally connected to one of the bell-crank-levers; means for supplying compressed air into the cylinder, a valve arranged to control the inlet and exhaust of air at each end of the cylinder, four actuating levers mounted one at each side of each truck and arranged to contact with the blocks near the track in the order stated, and operative connections between said actuating levers at each side of the car and the cylinder valve nearest that side of the car; said two levers at each side of the car having at the lower ends each an antifriction wheel, said wheels arranged at each side of the car one to contact with the outer block and the other with the inner block near the side of the track at which they operate; and means for restoring and holding said actuating levers in normal position with sufficient firmness to avoid accidental displacement of them. 95

3. For operation upon a railway track having curves and blocks fixed near the ends of the curves, a car arranged to move on said track and having trucks with axles and wheels; said trucks pivoted underneath the car to turn in passing over the curves, a double-acting cylinder fixed underneath the car and having a piston and piston rod extending therefrom beyond the cylinder, rods 115 operatively connecting the piston rod with the trucks to turn them, a reservoir arranged to receive compressed air from an air compressor and having a check-valve to prevent return of the air when the compressor is 120 not in active communication with the reservoir; two valves arranged to normally admit compressed air from the reservoir into both ends of the cylinder, each valve being constructed to shut off the air supply to the cyl- 130

- inder and exhaust air therefrom when turned to a certain position; actuating levers carried by the trucks and arranged to contact with the blocks near the track, and operative connections between said actuating levers and the valves, whereby each valve is alternately turned into active position when the car enters a curve and into idle position when the car leaves the curve.
- 5 4. For operation upon a railway track having a curve and blocks fixed near each end of the curve, a car arranged to move on said track and having trucks pivoted to turn underneath the car in passing over the curve, said trucks having axles and track wheels thereon, one or both wheels on each axle being revolute thereon and the axle having a central oil duct with a radial duct for oiling the wheel, and means for closing the central duct at the end of the axle; a truck-turning device carried by the car and having parts arranged to contact with the blocks near the track for the regulation of the action of the device, and means for operating
- 10 said truck-turning mechanism by compressed air.
5. For operation upon a railway track having a curve and blocks fixed near each end of the curve, a car arranged to move on said track and having trucks pivoted to turn underneath the car in passing over the curve, said trucks having axles and track wheels thereon; one or both wheels on each axle being revolute thereon, means for oiling said axles in the wheels, a truck-turning device carried by the car and having parts arranged to contact with the blocks near the track for regulating the action of the device, and means for operating the truck-turning device by compressed air, said track wheels having each a cylindrical face and a flange at right angles therewith.
- 15 30 35 40

In testimony whereof I affix my signature, in presence of two witnesses.
